United States Patent Office

Des. 224,107

Patented July 4, 1972

224,107

GLADHAND CONNECTOR

Victor Mastis, Hinsdale, Ill., assignor to The Berg
Manufacturing Company, Des Plaines, Ill.

Filed July 28, 1970, Ser. No. 24,190

Term of patent 14 years

Int. Cl. D23—01

U.S. Cl. D23—44

Fig. 6.

Fig. 5.

FIG. 1 is a front view of my design for a gladhand connector;

FIG. 2 is a side view of my design thereof;

FIG. 3 is an opposite side view of my design thereof;

FIG. 4 is a bottom view of my design thereof;

FIG. 5 is a rear view of my design thereof;

FIG. 6 is a top view of my design thereof;

FIG. 7 is a perspective thereof, viewed from the lower left of FIG. 1; and

FIG. 8 is a perspective thereof, viewed from the upper right of FIG. 1.

I claim:

The ornamental design for a gladhand connector, as shown.
